UNITED STATES PATENT OFFICE

WILLIAM F. GAMMETER, OF CADIZ, OHIO, ASSIGNOR TO WILLIAM K. GAMMETER, OF CADIZ, OHIO

DESIGN FOR A HOT-AIR REGISTER SHIELD

Application filed October 22, 1929. Serial No. 33,135. Term of patent 14 years.

To all whom it may concern:

Be it known that I, WILLIAM F. GAMMETER, a citizen of the United States of America, and resident of Cadiz, county of Harrison, and State of Ohio, have invented a new, original, and ornamental Design for a Hot-Air Register Shield, of which the following is a specification, reference being had to the accompanying drawings, in which—

I claim—

The ornamental design for a hot air register shield, as shown.

WILLIAM F. GAMMETER.
